UNITED STATES PATENT OFFICE.

WILLIAM BLANEY, OF MARBLEHEAD, MASSACHUSETTS, ASSIGNOR OF ONE-HALF TO
ARTHUR S. ADAMS, OF MARBLEHEAD, MASSACHUSETTS.

HEEL.

1,142,662.

Specification of Letters Patent.

Patented June 8, 1915.

Application filed November 18, 1914. Serial No. 872,826.

To all whom it may concern:

Be it known that I, WILLIAM BLANEY, of Marblehead, in the county of Essex and State of Massachusetts, have invented certain new and useful Improvements in Heels; and I do hereby declare the following to be a full, clear, and exact description of the invention, such as will enable others skilled in the art to which it appertains to make and

10 use the same.

The primary object of this invention is to provide means for attaching yielding heel lifts without the use of nails or screws, thereby avoiding all liability of scratching 15 smooth or polished floors, decks, etc., and avoid not only the wear of the exposed surfaces of the fastening means, but also the accumulation of dirt or snow in the sockets in which such fastening means has heretofore been countersunk.

A further object is to provide improved 20 means for securing yielding heel lifts in place by means which while permitting such lifts to be changed from one heel to the other 25 to insure uniformity in wear, will effectively prevent any accidental displacement of the yielding lift.

In the accompanying drawing, Figure 1 30 is a view in perspective. Fig. 2 is a view showing the fixed and removable lifts separated. Fig. 3 is a central longitudinal section view.

Referring to the drawings, 1 designates a 35 fixed lift or heel section formed with two transverse ribs 2 of dovetail formation in cross section. This fixed lift may be made of wood, leather, or any suitable fiber.

3 is the removable lift or heel section which is formed with two transverse grooves 40 4 designed to receive the transverse ribs 2 of the fixed lift so that the removable lift may be attached and detached by a relative transverse sliding movement between the two lifts. The removable lift is formed of 45 rubber or other suitable resilient material. After the two lifts have been secured together by a relative lateral movement, they are locked by means of a key preferably in the form of a rod 5 which projects from the 50 breast of the heel and longitudinally of the latter transversely through the interengaging portions of the two lifts, that is to say, through the ribs of the fixed lift and those portions of the removable lift adjacent to 55 the grooves of the latter. This rod may be

secured in place by any suitable means, but I prefer to form it with an external thread for fitting in threaded bushings in the walls of the removable lift, the end of said key-rod being grooved to enable it to be readily turned by an ordinary screw-driver. The end of this key-rod is flush with the forward end of the heel so as to guard against dirt getting in between the lifts. To further provide against any accidental displacement 60 of the removable lift and to hold it firmly along its edges against the ingress of dirt or water, I employ coöperating studs and sockets. As shown in Fig. 2 the lower face of the fixed lift may have a series of short studs 65 6 projecting at right-angles therefrom and designed to fit in sockets 7 of the removable lift, the engagement and disengagement of the studs and sockets being effected by a slight bending outward of the removable 70 lift as it is being adjusted to or removed from the heel. These studs and sockets so hold the removable lift that there is no danger of its being accidentally knocked off or separating from the fixed lift so that foreign substances might enter between the two 75 lifts.

I have shown the removable lift as having sections of nonslippping material cored 80 therein. For this purpose I preferably employ pieces of cork 8, the lower surfaces of which are designed to be flush with the surface of the removable lift.

The advantages of my invention will be 85 readily appreciated by those skilled in the art. It will be seen that there are no sockets in the lower face of the removable lift and no exposed fastening means, and also that by reason of the transversely arranged interengaging portions the outer heel 90 section is firmly secured, but that in addition thereto the parts are locked against all 95 possibility of displacement by the centrally disposed key passing through the overlapping portions of the lifts. The use of the 100 interlocking studs and sockets is not absolutely essential, but in some circumstances it is advisable. By means of my invention the outer lift may be readily removed so as to be transferred from one heel to the other 105 of a pair of shoes so as to insure evenness of wear.

I claim as my invention:

1. A shoe-heel having a fixed lift and a removable lift, said lifts having interen- 110

gaging slidably connected portions extending transversely of the heel, and studs projecting at right angles from one of the lifts, the other lift having sockets to accommodate
5 said studs, said studs and sockets being constructed and arranged to prevent separation of the lifts in a direction normal to their faces.

2. A shoe-heel having a fixed lift and a
10 removable lift, said lifts having interengaging slidably connected portions extending transversely of the heel, studs projecting at right angles from one of the lifts, the other lift having sockets to accommodate said

studs, said studs and sockets being constructed and arranged to prevent separation of the lifts in a direction normal to their faces, and securing means extending from the breast of the heel and longitudinally of the latter and transversely through said interengaging 20 portions for locking them together.

In testimony whereof, I have signed this specification in the presence of two subscribing witnesses.

WILLIAM BLANEY.
